UNITED STATES PATENT OFFICE.

PERLEY L. KIMBALL, OF BELLows FALLS, VERMONT, ASSIGNOR TO VERMONT FARM MACHINE COMPANY, OF BELLows FALLS, VERMONT, A CORPORATION.

CENTRIFUGAL CREAM-SEPARATOR.

No. 806,346.

Specification of Letters Patent.

Patented Dec. 5, 1905.

Application filed March 25, 1905. Serial No. 251,925.

To all whom it may concern:

Be it known that I, PERLEY L. KIMBALL, a citizen of the United States of America, residing at Bellows Falls, in the county of Windham and State of Vermont, have invented certain new and useful Improvements in Centrifugal Cream-Separators, of which the following is a specification.

This invention has for its principal objects the facilitation of the separation of cream from whole milk within a centrifugal separator by a peculiarly-organized structure for subdividing the mass of liquid operated upon, the drawing off of the skim-milk from the extreme inner periphery of the centrifugal bowl to insure the maximum cream impoverishment of the same, and the location of discharge-orifices for the cream and skim-milk, respectively, inside the limits of substantially the same radial distance from the axis of rotation, but separated from each other by solid division-walls, while at the same time securing the separability of all parts of the apparatus in such manner as to make the interior of its several compartments and passages readily accessible for cleansing.

The embodiment of this invention is specifically exemplified by the following-described mode of construction, which is illustrated by the accompanying drawings, wherein—

Figure 1 is a central vertical section of the centrifugal cream-separator with its constituent parts in their normal operative positions, but without the radial partitions in the skim-milk passage between the two divisions of the duplex cover. Fig. 2 is a plan view of the top of the apparatus and of a horizontal section taken through the necks of the duplex cover at the location indicated by dotted line $\alpha\alpha$ on Fig. 1. Fig. 3 is a plan view of the circular base-plate upon which rests the subdividing devices within the centrifugal bowl, together with their lateral supports and the axially-located milk-feeding tube. Fig. 4 is a plan view of one of the subdividers. Fig. 5 is an elevation of two subdividers in their mutually-interlocked position. Fig. 6 is a plan view, and Fig. 7 a side elevation, of the inner division of the duplex cover, having affixed thereto the radial partitions which subdivide the skim-milk passage between the two divisions of that cover.

Referring to the drawings, A is the bowl of

the centrifugal cream-separator, secured to and supported upon the spindle B in the usual and well-known manner.

Within the centrifugal bowl and concentric to the axis thereof is placed the feed-tube a , which receives support at its lower end by fitting over a cylindrical boss projecting upward from the bottom of the centrifugal bowl and which near its upper end passes through a circular aperture in the cover and is there laterally supported by the latter.

Surrounding the feed-tube a , near to its lower end and to the bottom of the centrifugal bowl, is the circular base-plate b , which is fastened securely to the feed-tube and extends horizontally to close proximity with the interior cylindrical periphery of the bowl.

The feed-tube a and the base-plate b , attached thereto, are kept from turning when in normal operative position by a slot in the lower end of the feed-tube which fits over a pin secured to the bottom of the bowl. The lower end of the feed-tube is also provided with apertures for the outward flow of the milk underneath the base-plate, and the latter is perforated with a circular series of holes c , arranged concentrically to the axis of the bowl and opening into the annular space which is surrounded by the subdividing devices presently to be described.

The mechanical means for facilitating the separation of cream and blue milk from each other consists of a peculiarly-organized structure by which the mass of whole milk introduced into the centrifugal bowl to be therein operated upon is subdivided into what may properly be designated as "thin liquid fillets," each separately inclosed in a correspondingly-shaped compartment wherein the distance to be traveled by the cream globules in order to become separated from the blue milk with which they are associated is the least practically possible, while at the same time the structure itself when the apparatus is taken apart is capable of being readily separated into its component elements to such an extent as to expose their interior surfaces to easy accessibility for cleansing. The individual component element of this structure is a single subdivider consisting of a flat annular plate d , which has affixed to both of its opposite sides and projecting at right angles therefrom a cyclic series of parallel blades e , form-

ing involute curves and which may be provided with perforations f through it between such blades. Several of these subdividers are superposed in such manner as to cause their opposed series of involute blades to interlock with each other, and thus to convert each space between two consecutive blades into two thin tubular spiral passages leading from the inner to the outer margins of the annular plates from which those blades project.

When, as shown in the drawings, the two cyclic series of parallel involute blades e , projecting from opposite sides of the annular plate d and constituting therewith an elemental subdivider, are coincident with each other, so that every separate blade upon one side is in the same curved plane with a corresponding blade upon the other side, and when also the annular plate d is perforated between the successive blades, so as to permit the flow of liquid transversely across each coincident pair of blades, the principal functions of such perforated plate are to furnish a rigid support for the coincident cyclic series of involute blades upon both sides of it and to present a fixed abutment for the free lateral edges of the blades of the next adjacent member or members of the series of interlocked subdividers to bear against.

Rigidly secured to the feed-tube a and projecting laterally from its outer surface in planes radial to the axis thereof are four wings g , perforated with holes h and carrying upon their outer edges bearing-strips i , over which the annular plates of the subdividers closely fit and which serve as lateral supports for the same. One of these vertical bearing-strips extends radially farther out than the others, and to accommodate it a corresponding notch j is cut in the inner edge of the annular plate d of each subdivider, so as to keep the latter from turning. When a series of these elemental subdividers, superposed and interlocked, as hereinbefore described, is introduced within the centrifugal bowl, the whole subdividing structure thus constituted rests upon the base-plate b and forms within the annular space between the internal cylindrical periphery of the centrifugal bowl and an axially-concentric cavity therein an assemblage of closely-adjacent relatively small and narrow tubular spiral passages or ducts open at their ends and extending through such annular space obliquely across planes radial to the axis of the bowl. These subdividers should be so constructed that when thus assembled to form a superposed and interlocked series within the centrifugal bowl their involute blades will run in such direction as to have their outermost ends point toward the direction in which they and the centrifugal bowl are intended to be rotated. Thus in the apparatus herein concretely illustrated the centrifugal bowl is assumed to be rotated from left to right when

viewed from above its top, or, in other words, in the direction of movement of the hands of a clock, and accordingly the blades of the subdividers are mounted and assembled so as to point in the same direction. This relationship of position to direction of rotation tends to retard the outward flow of the liquid within the tubular spiral passages of the subdividing structure, and thus secures more time for the escape of the cream from the milk at any given point. The economy and convenience of such a subdividing structure will be manifest from the fact that if each elemental subdivider contains eighteen blades on each side of its annular plate and has a width of, say, five-eighths of an inch, each blade being a little less than five-sixteenths of an inch in width by reason of the thickness of the supporting-plate, it will take only nine of such subdividers to occupy three and one-half inches in axial depth, and where two adjacent subdividers are interlocked the space between each two consecutive annular plates will be subdivided by thirty-six involute blades into as many involute ducts, and yet when the structure of the dimensions just given is taken apart for cleansing there are only nine separate pieces to be taken care of and reassembled for further use, whereas in such prior structures as have accomplished the subdivision of the same annular space to even an approximately comparable degree with suitable provision for accessibility in cleansing the number of separate subdividing elemental pieces to be taken apart and replaced has been very considerably greater and has required much more time and care for proper management. The series of superposed and interlocked subdividers thus introduced into the centrifugal bowl is held securely down when the apparatus is in normal operative condition by an annular flange z , which projects downward from the under side of the cover or, in the specific apparatus herein described, from the base of the inner division of the duplex cover k' , and which bears firmly upon the topmost subdivider of the series. This downwardly-projecting flange z is made of sufficient depth in a direction parallel to the axis of the centrifugal bowl to provide an otherwise-unobstructed space above the subdividing structure for the final adjustment of relative position therein between the cream and skim-milk just before their discharge from the centrifugal bowl. The flange itself is perforated at intervals with holes which permit the flow of the liquid through it, and obviously it will perform its described functions whatever may be the precise contour of its walls, provided its general outline as a whole is annular in shape and it is traversed by lateral passages.

The centrifugal cream-separator to which the improvements constituting the present invention are applied is provided with a du-

plex cover which consists of separable inner and outer divisions, each comprising an annular base k k' and a tubular neck l l' , and these two divisions contain between them the entire passages for the delivery of the skim-milk from the centrifugal bowl. The annular base k' of the inner division of the duplex cover is substantially equal in diameter to the cylindrical cavity of the centrifugal bowl, and when all parts of the apparatus are in normal operative position the circumferential periphery of this annular base k' is encompassed by a groove m , located in the immediately surrounding wall and affording space for the escape of the skim-milk while under centrifugal stress at the extreme outmost portions of its mass into the discharge-passages between the two divisions of the duplex cover. This groove m , encompassing the circumferential periphery of the annular base k' of the inner division of the duplex cover, may be formed in the interior periphery of a flange n , depending from approximately the circumferential portion of the margin of the annular base k of the outer division of the duplex cover, or it may be formed in the interior periphery of the upper part of the wall of the centrifugal bowl itself, according to the mode in which the outer division of the duplex cover is secured upon the top of the centrifugal bowl.

The discharge-passages for the delivery of the skim-milk from the centrifugal bowl lead radially inward from the groove m , encompassing the circumferential periphery of the annular base k' of the inner division of the duplex cover, between that annular base and the annular base k of the outer division of the duplex cover, to an annular diaphragm o , which bridges the space between the tubular necks l l' of these two divisions, thence through orifices p in that diaphragm, so located as to have their extreme outer edges at substantially the same radial distance from the axis of rotation as is the outer edge of the aperture s for the final discharge of the cream when adjusted to its outermost position. After passing the orifices p through the annular diaphragm o the skim-milk is delivered outward at or near the top of the tubular neck of the outer division of the duplex cover. In order to keep the skim-milk from excessive lateral swirl in its inward flow toward the axis of rotation, the space between the annular bases of the inner and outer divisions of the duplex cover is more or less subdivided by radial partitions q .

The discharge-passage for the cream is a tube r , opening through and extending from the bottom of the annular base k' of the inner division of the duplex cover near to the bore of its tubular neck l' and parallel with the axis thereof up to the top of the same. The upper end of this cream-discharge tube

r is screw-threaded inside and is there closed by a screw-plug which has a small hole s through it lengthwise and very close to its periphery for the final exit of the cream. By turning this plug the discharge-orifice s can by virtue of its eccentric position be adjusted at distances from the axis of rotation of the centrifugal bowl varying within a range nearly equal to the diameter of the cream-tube r itself, and thus cream of predetermined density can be drawn from the latter during the operation of the machine.

The annular diaphragm o is made to close tightly the space between the outer edges of the orifices p through it and the inner wall of the tubular neck l of the outer division of the duplex cover, and the location of these orifices in the position already mentioned is accomplished by contracting the neck l' of the inner division of the said cover at that place to such extent as to cause a considerable portion of the walls inclosing the cream-discharge passage r to project laterally beyond the outer surface of the walls of the neck l' thus contracted. In this way the exit of the skim-milk from the inwardly-leading passages between the two divisions of the duplex cover is provided for at a radial distance from the axis of rotation which it is desired that the dividing-circle between the blue milk and the cream shall assume at the upper part of their separated masses within the centrifugal bowl and which will manifestly be substantially the same as the radial distance from the axis of rotation of the liquid annulus of skim-milk standing up just below the diaphragm at the outer edges of the exit-apertures p under the action of centrifugal stress. Moreover, since the tubular discharge-passage r for the cream is so located with relation to the exit-orifices p for the skim-milk that the extreme outer edges of the latter are at substantially the same radial distance from the axis of rotation as is the outer edge of the orifice s for the final exit of the cream when adjusted to its outermost position it follows that the lower end of the cream-discharge tube r stands diametrically across the top of the wall of cream just inside the liquid annulus of the blue milk within the centrifugal bowl.

Above the outer margin of the annular diaphragm o is an inwardly-projecting annular offset t upon the tubular neck l of the outer division of the duplex cover, and between the under side of such annular offset and the outer margin of the upper side of the annular diaphragm beneath it are provided means for their engagement, so as to form a tight joint when all parts of the apparatus are in normal operative position—such, for instance, as a groove u , containing packing in the one and a corresponding beading v upon the other to enter such groove and to press upon the packing therein.

For the purpose of aiding to keep the two divisions of the duplex cover in undisturbed concentric relation to each other the tubular neck l' of the inner division above its contracted portion is enlarged in diameter to fit and be closely embraced by the upper end of the tubular neck l of the outer division, and the apertures for the escape of the skim-milk from the final discharge-cavity above the dia-

5 phragm σ are made through the wall of the tubular neck l of the outer division of the duplex cover just below the enlargement of the top of the tubular neck l' of the inner division.

15 The outer division of the duplex cover is provided with a flange n , depending from approximately the circumferential margin of its annular base k to make screw connection with the upper portion of the centrifugal bowl. If such screw connection is located upon the outside of the centrifugal bowl, the upper edge of the cylindrical wall of the latter is made to abut against the lower side of the annular base k of the outer division of the duplex cover just inside of the flange depending therefrom, with packing between them; but if the screw connection is located upon the inside of the centrifugal bowl, as in the structure specifically delineated, the 20 flange n , depending from the outer margin of the annular base k of the outer division of the duplex cover, fits within an annular enlargement upon the upper portion of the centrifugal bowl, and the upper edge of the latter abuts against a circumferential extension of the annular base k of the outer division of the duplex cover outside of the flange depending therefrom, and the joint thus made by the abutting parts is there suitably packed.

25 30 35 40 45 50

In order to prevent the inner division of the duplex cover from turning while the outer division of that cover is being screwed down upon the centrifugal bowl and to guide such inner division of the cover in its descent so as to bring the flange projecting downward from its base squarely upon the top of the series of superposed and interlocked subdividers without any twisting strain, a spline w is formed upon the outer surface of the feed-

55 60 tube x and a corresponding groove y is cut in the bore of the inner division of the cover, so that the two fit and slide upon each other. It will be seen that the entire passages for the delivery of the skim-milk from the centrifugal bowl are contained between the two divisions of the duplex cover and that when the apparatus is taken apart these two divisions are separable one from the other in such manner as to expose all the passages embraced between them and to render them easily accessible for cleansing.

I claim—

1. In a centrifugal cream-separator, a device for facilitating the separation of the cream

from the blue milk, which consists of a series 65 of superposed and interlocking subdividers, each made of a flat annular plate having affixed to both opposite sides and projecting at right angles therefrom, a cyclic series of parallel blades arranged in involute curves, and which when its parts are in normal, operative position is located within the annular space between the internal periphery of the centrifugal bowl and an axially-concentric central cavity therein, and forms an assemblage of closely- 70 adjacent, relatively small, tubular, spiral ducts, open at their ends and extending through such annular space obliquely across planes radial to the axis of the bowl.

2. In a centrifugal cream-separator a series 80 of superposed and interlocking subdividers, each consisting of a flat annular plate which has affixed to both of its opposite sides and projecting at right angles therefrom, a cyclic series of parallel blades forming involute curves; 85 and an annular flange which projects downward from the under side of the cover, to bear upon the top of the series of such subdividers when thus assembled within the centrifugal bowl, for steadyng the same in place, and for 90 securing above them an otherwise unobstructed space, and which is perforated at intervals to allow the flow of liquid through it laterally.

3. In a centrifugal cream-separator a series 95 of superposed and interlocking subdividers, each consisting of a flat annular plate which has affixed to both of its opposite sides and projecting at right angles therefrom, a cyclic series of parallel blades forming involute curves, and which has perforations through it between 100 such blades; the whole being so assembled and arranged as to occupy an annular space between the internal periphery of the bowl and an axially-concentric central cavity therein, and to have the outer ends of the involute blades 105 pointing toward the direction of revolution intended to be given to the centrifugal bowl.

4. A subdivider for use in a centrifugal cream-separator, consisting of a flat annular plate which has affixed to both of its opposite 110 sides and projecting at right angles therefrom a cyclic series of parallel blades forming involute curves.

5. A subdivider for use in a centrifugal cream-separator, having in outline an annular 115 shape and consisting of two series of parallel blades forming involute curves and arranged in coincident pairs on opposite sides of a rigid support therefor, with intermediate passages adapted to permit the flow of liquid transversely across the structure from one side to the other between consecutive blades.

6. In a centrifugal cream-separator, a series 120 of superposed and interlocking subdividers, all of similar annular outline, and each consisting of two cyclic series of parallel blades forming involute curves and arranged in coincident pairs on opposite sides of a rigid sup-

port therefor, which is provided with intermediate passages adapted to permit the flow of liquid transversely across the coincident pairs of blades, and against which, as an abutment, the free lateral edges of the blades of the next adjacent member or members of the series of interlocked subdividers bear.

7. In a centrifugal cream-separator which is provided with a duplex cover, consisting of 10 separable inner and outer divisions, each comprising an annular base and a tubular neck, and the two divisions containing between them the entire passages for the delivery of the skim-milk from the centrifugal bowl; exits 15 which lead directly from those passages outside of the walls of the neck of the inner division of such cover, and which are so located that their extreme outer edges are at substantially the same radial distance from the axis 20 of rotation as is the outer edge of the aperture for the final discharge of the cream when adjusted to its outermost position; and means for tightly closing the space between such exits and the outer division of the said cover.

25 8. In a centrifugal cream-separator which is provided with a duplex cover, consisting of separable inner and outer divisions, each comprising an annular base and a tubular neck, and the two divisions containing between them 30 the entire passages for the delivery of the skim-milk from the centrifugal bowl; an inner division of such cover having an annular base which is substantially equal in diameter to the cylindrical cavity of the centrifugal 35 bowl, and an annular groove which when the parts are all in normal, operative position, is located in the wall immediately surrounding the circumferential periphery of such annular base of the inner division of the cover, and 40 which affords space for the escape of the skim-milk at the extreme outermost portions of its mass into the discharge-passages between the two divisions of the cover.

9. In a centrifugal cream-separator which 45 is provided with a duplex cover, consisting of separable inner and outer divisions, each comprising an annular base and a tubular neck, and the two divisions containing between them the entire passages for the delivery of the 50 skim-milk from the centrifugal bowl; an inner division of such cover which has its tubular neck contracted sufficiently to permit a considerable portion of the walls inclosing the 55 cream-discharge passage to project laterally beyond the outer surface of the walls of such contracted neck; and an annular diaphragm which bridges the space between such contracted neck and the surrounding neck of the outer division of the cover, and which contains 60 apertures for the exit of the skim-milk, so located that their extreme outer edges are at substantially the same radial distance from the axis of rotation as is the outer edge of the

aperture for the final discharge of the cream when adjusted to its outermost position. 65

10. In a centrifugal cream-separator which is provided with a duplex cover, consisting of separable inner and outer divisions, each comprising an annular base and a tubular neck, and the two divisions containing between them 70 the entire passages for the delivery of the skim-milk from the centrifugal bowl; an outer division of such cover which has a flange depending from the outer margin of its annular base to make screw connection with the upper 75 edge of the centrifugal bowl; an inner division of such cover which has its annular base of substantially equal diameter to that of the internal periphery of the flange aforesaid upon the outer division of the cover; and an annular groove formed in the inner wall of that flange, which, when the outer division of the cover is screwed down upon the centrifugal bowl so as to bring all parts of the apparatus 80 into normal, operative position, immediately 85 surrounds the circumferential periphery of the annular base of the inner division of the cover, and affords space for the escape of the skim-milk at the extreme outermost portions 90 of its mass into the discharge-passages between the two divisions of the cover.

11. In a centrifugal cream-separator which is provided with a duplex cover, consisting of separable inner and outer divisions, each comprising an annular base and a tubular neck, 95 and the two divisions containing between them the entire passages for the delivery of the skim-milk from the centrifugal bowl; an annular diaphragm which projects outwardly from the neck of the inner division, which 100 bridges the space between this neck and the inner surface of the neck of the outer division, and which contains apertures for the exit 105 of the skim-milk into the final discharge-cavity therefor; an inwardly-projecting annular offset upon the outer neck above the said diaphragm; and means for forming a tight joint between such offset and diaphragm when the parts of the apparatus are in normal, operative 110 position.

12. In a centrifugal cream-separator which is provided with a duplex cover consisting of separable inner and outer divisions, each comprising an annular base and a tubular neck, and containing between them the passages for 115 the delivery of the skim-milk from the centrifugal bowl; a laterally-perforated annular flange projecting downward from the base of the inner division of the cover and adapted to bear upon the top of the series of subdividers 120 assembled within the centrifugal bowl.

13. In a centrifugal cream-separator which is provided with a duplex cover consisting of separable inner and outer divisions, each comprising an annular base and a tubular neck, 125 and containing between them the passages for

the delivery of the skim-milk from the centrifugal bowl; a laterally-perforated annular flange projecting downward from the base of the inner division of the cover and adapted to
5 bear upon the top of the series of subdividers assembled within the centrifugal bowl; and means for keeping such inner division of the

cover with its said flange from axial turning when the outer division of the cover is being screwed to its seat.
